UNITED STATES PATENT OFFICE.

ROBERT J. BELL, OF OCEAN VIEW, VIRGINIA.

VENDING APPARATUS.

1,123,071.

Specification of Letters Patent. Patented Dec. 29, 1914.

Application filed December 4, 1913. Serial No. 804,717.

To all whom it may concern:

Be it known that I, ROBERT J. BELL, a citizen of the United States, residing at Ocean View, in the county of Norfolk and State of Virginia, have invented new and useful Improvements in Vending Apparatus, of which the following is a specification.

This invention relates to vending apparatus.

An object of the invention is the provision of apparatus of this character for vending packages of cigarettes, tobacco in bag form, plug form, etc.

Another object of the invention is the provision of mechanism whereby different grades or selected brands of tobaccos may be readily visible to the purchaser and actively delivered to him in predetermined

quantities on the deposit of a coin.

Another object of the invention is the provision of vending apparatus wherein packages from one or a particular package containing division thereof may be freely delivered without accidentally causing a delivery of packages from other sub-divisions of the machine.

Another object of the invention is the provision of vending apparatus wherein packages from one of the package containing divisions thereof may be only delivered to the person on a deposit of a plurality of coins of different and designated denominations.

Another object of the invention is the provision of delivering mechanism which will be positively set to a released condition on the deposit of a coin and which will remain in such condition until actually manipulated by the purchaser.

Another object of the invention is the provision of vending apparatus wherein the packages may be partly advanced to the purchaser and in a manner which will permit the purchaser to entirely remove the packages from the machine after a prescribed operation of the delivering mechanism.

Another object of the invention is the provision of vending apparatus wherein packages of varying sizes may be properly accommodated and associated with the delivering mechanism for accurate delivery.

A further object of the invention is the provision of vending apparatus including a casing which is sub-divided into a plu-

rality of compartments for packages of tobacco of different brands and means whereby all of the compartments or divisions may be exposed to permit of a convenient refilling of the machine.

A still further object of the invention is the provision of vending apparatus wherein the coins or actuating objects which are employed for the purpose of controlling the delivering mechanism may be first placed on view for the benefit of the salesman, thus enabling him to instantly ascertain as to whether or not coins of proper value have been employed by the purchaser.

With these and other objects in view, the invention consists of certain novel features of construction, combination and arrangement of parts, as will be hereinafter described and claimed.

In the accompanying drawings:—Figure 1 is a perspective view of the vending apparatus; Fig. 2 is a vertical section therethrough; Fig. 3 is a horizontal section therethrough, showing that mechanism of the package containing division of the machine which is influenced on the deposit of a plurality of coins of given denominations; and Fig. 4 is a similar view through the machine, showing another package containing division thereof and its delivering mechanism which is controlled by a single coin.

The machine comprises a casing 1 provided with coin chutes 2, 3, 4, 5, 6 and 7, all of which being provided with a single slot 8, excepting the chute 7. The latter is provided with coin slots 9 and 10, which in the present instance are shown as being of different sizes, so as to accommodate coins of different values.

The casing is provided with a front wall 11 having a plurality of transparent display panels 12, through which commodities to be vended may be viewed by the purchaser. This wall is provided along its lower edge 100 with a plurality of depending pins 13, which extend in corresponding sockets 14 formed in the offset portion 16 of the casing. The said wall 11 carries a suitable lock 16 that may be secured with the adjacent top wall of the casing, so that the mentioned wall 11 may be securely held against removal under ordinary conditions, while by manipulating the lock, the wall 11 may be removed by the owner of the machine and 105 the interior of the casing thus exposed to enable one to readily refill the machine with

packages to be vended. The casing is divided interiorly into a number of sub-divisions which correspond with the number of coin chutes hereinbefore mentioned, the said chutes being located directly behind said sub-divisions for a purpose to be herein-after explained.

At the bottom of each of the compartments or sub-divisions, excepting that sub-division or compartment with which the coin chute 7 is associated, is a delivering mechanism 16, consisting of a horizontal slide 17, on which the packages to be vended are adapted to rest, as clearly shown in Fig. 2. This slide is provided with a vertically-rising delivering projection 18 which normally rests directly at the back of the lower package and which is designed to move the package in the direction of the delivering tube 19 at the front of the machine on a prescribed manipulation of the slide. The said tube 19 extends approximately at an obtuse angle to the direction of the slide, so as to present the package to the angular position shown in dotted lines in Fig. 2. The inner open end of the tube is provided with a gravitationally operated gate 20, which is opened through the sliding action of the package on the delivery of the latter and which is normally closed so as to prevent one from taking the packages by implements or devices that may be inserted through the delivering tube 19. In order to prevent the tampering of the gate 20 and to assure a positive locking of the same, I provide on the slide 17 at a point forwardly of the gate 20, an upstanding lug 20', which is better illustrated in Fig. 3 of the drawing. The lower wall of the delivering tube 19 directly overlies the slide 17, so that the packages may be freely guided into the tube when the slide is moved to a delivering position. At the front the slide is provided with an angular extension 21, to which is secured a hand-actuated knob 22.

At the back, the slide 17 is provided with a keeper plate 23 having a slot 24 therein.

Within the casing is a pivoted dog 25 having a locking end 26 which is normally projected through the slot 24 of the keeper plate 23, and which is provided with a hook 26 that extends over one side of the keeper plate normally, so as to hold the slide against movement. The surface 27 of the hook of said pivoted dog is tapered for a purpose to be hereinafter explained. Said dog is provided with a tail 28, the terminals of which being curved longitudinally and extended in to the adjacent coin slot, as shown in Fig. 2, completely traversing the slot, whereby to obstruct the passage of the coin in the slot. The tail of the said dog also extends through a slot 29 in one of the walls of the coin slot. The locking end of the dog is normally positioned relatively of

the wall 30 of the slot 24, whereby it is slightly spaced therefrom and for a distance exceeding the width of the shoulder of the hook 26. This construction is preferred in order that the said locking end of the dog may be brought to engage against the wall 30 of the mentioned slot 24 when the weight of the coin is directly supported upon the tail 28 of the dog. It is now seen that under the applied weight or action of the coin against the tail of the pivoted dog, the keeper-engaging end of the latter will be maintained in a predetermined position relatively of the keeper and the slide 17 of the delivering mechanism is positively held released for a delivery of a single package to the purchaser. On the return of the slide the keeper 23 will engage beneath the surface 27 of the pivoted dog and the latter will be automatically re-set for a subsequent action on the deposit of a coin.

In order to effect an automatic return of the slide after the delivery of a single package I provide a return spring 31, one end of which being engaged against an integral portion 32 of the slide, while the opposite end of the spring is operatively associated with a lug 33 of the casing.

As it is the purpose to employ an apparatus wherein may be placed on sale packages of cigarettes or the like of different brands and different values I propose that the pivoted dogs 25 will be proportioned and counterbalanced in a manner which will make them clearly responsive to coins of different weights and denominations. All of the coin chutes, excepting the chute 7, are intended for the receipt of a single coin. The chute 7 is designed so as to permit of the delivery of a package on the deposit of two coins, namely, in the present instance, one coin of a five-cent denomination, and a second coin of a ten-cent denomination, hence the provision of two separate and distinct ways or passages 34 and 35. On reference to Fig. 3, it is seen that these passages open directly onto the tails of dogs 36 and 37, the locking ends of which are shown at 38 and are normally engaged with a keeper 39 which is substantially identical with the form of keeper 23 hereinbefore referred to. Through this arrangement of a set of dogs, it is seen that it will be necessary in order for the operator to receive the package to deposit in the subdivisions of the chute, coins of the described denominations.

Beneath the coin controlled dog of each chute is a spring 40 having a coin-engaging end 41 which extends in the direction of a transparent panel 42 arranged in the wall of the casing at the back thereof so that after the coin drops from the dog it will be caught by the spring and then put on display to the salesman, by way of said transparent panel. The weight of the succeeding

coin as it leaves the dog is adapted to cause the coin held by the spring to be deposited in a coin drawer 43 which is slidably or otherwise suitably mounted in the bottom of 5 the casing.

In order that the cigarettes or articles of merchandise may be satisfactorily distinguished from each other, I preferably mount upon the front of the casing in the presence 10 of each of the article containing sub-divisions thereof a guide 44, in which may be mounted a card 45 containing the name of the article on sale.

While it is only mentioned that at least 15 one of the chutes for receiving the coins is sub-divided into two ways for the passage of the coins, it is to be understood that any number of ways may be provided, and that they may be constructed to receive coins in 20 which all are of the same denomination if such necessity may arise.

I claim:

In vending apparatus a merchandise mag-

azine, a coin chute, one of the walls of the chute having a stop shoulder, a pivoted dog 25 having a tail extending into the chute, a slide mounted in the magazine, a slotted keeper plate carried by the slide, a nose formed on the dog and provided with a beveled surface, the tail of the dog having 30 free engagement with the shoulder so that the latter serves to hold the nose of the dog in a position to permit of the passage thereof through the slot of said keeper, the dog when engaged with the keeper serving to 35 hold the slide against movement in one direction and means for holding said slide against movement in an opposite direction when the nose of the dog is engaged with the keeper.

In testimony whereof I affix my signature in presence of two witnesses.

ROBERT J. BELL.
